UNITED STATES PATENT OFFICE.

RALPH L. LEE, OF DAYTON, OHIO, ASSIGNOR TO DELCO-LIGHT COMPANY, OF DAYTON, OHIO, A CORPORATION OF DELAWARE.

DRIVING MECHANISM.

Application filed August 28, 1924. Serial No. 734,786.

The present invention relates to a power operated driving mechanism for a work machine and particularly to the driving mechanism for the washing and the wringer apparatuses.

5 One of the objects of the present invention is to reduce the cost and facilitate the manufacture and repair of a work machine by providing a driving mechanism which can 10 be readily assembled or can be readily disassembled for the inspection and repair thereof.

The laundry machine to which the present invention is applicable is of that type in 15 which separate driving mechanism and motors are used for the washing apparatus and the wringing apparatus.

Another object of the invention is to provide a laundry machine of the present type 20 in which portions of the driving mechanism for the washing apparatus and wringing apparatus are interchangeable, thus reducing the cost and facilitating the manufacture thereof.

25 A still further object is to isolate the electrical circuits for the motors from water and lubricant.

Further objects and advantages of the 30 present invention will be apparent from the following description, reference being had to the accompanying drawings, wherein a preferred form of the present invention is clearly shown.

In the drawings:

35 Fig. 1 is a perspective view of a driving unit for the wringing apparatus;

Fig. 2 is an end view of a bracket adapted to support the wringer apparatus and the driving unit shown in Fig. 1;

40 Fig. 3 is a perspective view of a driving unit for the washing apparatus;

Fig. 4 is a fragmentary end view of a support for the washing apparatus driving unit and the washing apparatus;

45 Fig. 5 is a fragmentary sectional view of the driving mechanism for the wringer, this section being taken on line 5—5 and 5'—5' of Fig. 6;

Fig. 6 is a fragmentary sectional view 50 taken on line 6—6 of Fig. 5; and

Fig. 7 is a fragmentary view partly in section and partly in elevation of the driving mechanism for the washing apparatus.

Referring to the drawings, the apparatus 55 herein shown is particularly applicable to

that type of laundry machine in which individual power driving units 24 and 25 are provided for a washing apparatus 22 and a wringing apparatus 23 respectively. One form of such laundry machine is shown in 60 my copending application, Serial No. 629,201, filed March 31, 1923. These driving units are each provided with a reversible motor for causing the oscillation of the washing apparatus and for reversing the direction of rotation of the wringer rollers.

Referring more particularly to the drawings, a supporting frame includes side frames one of which is shown at 26. The upper ends of side frames 26 are apertured to 70 receive trunnions 32 which pivotally carry a tub 35. A sector 40 is pivotally mounted upon a trunnion 32 and is disposed between the side frame 26 and the tub 35 and is connected for driving the tub preferably 75 through a leaf spring (not shown). The sector is driven by the driving unit 24, to be described.

A hollow bracket 50 of wringing apparatus 80 23 is rotatably mounted on the laundry machine. A clothes wringing device 51 is detachably secured to one side of the bracket 50 by bolts 52. The wringing device 51 is provided with wringer rolls, the shafts of 85 which carry cooperating gears 55 and 56 respectively. The bracket 50 forms a gear housing 58 and supports therein a gear 59, the axis of which is located in alinement with one of the wringer roll shafts. The side of the gear 59 facing the wringer roll is 90 provided with notches 60 which are adapted to receive the ears 61 of a universal joint coupling 62. Coupling 62 also includes ears 63 and 64 extending in the opposite direction from that of ears 61. The ears 64 are 95 formed by splitting the walls of the ears 63 and then bending the ear portions 64 outwardly. In this manner a slot 65 is formed, which is adapted to receive a pin 66 secured to one of the wringer rolls. Movement of 100 the gear 59 will cause motion to be transmitted through the coupling 62 to the wringer rolls.

The gear housing 58 is flared outwardly to 105 form a compartment 68 having an end wall 69. The wringer driving unit 25 is detachably mounted upon the bracket 50 and adjacent the compartment 68 by bolts 70. The driving unit 25 includes a gear housing 71, 110 the upper end of which merges into an end

cap 72 for a motor frame 73. The armature shaft 74 of the motor extends within the gear housing 71 and forms a driving worm 75. Worm 75 cooperates with a worm gear 76 to drive an operating shaft 77 which is journaled within a bearing 78 formed by one wall 79 of the gear housing 71. Shaft 77 extends through wall 79 and within the compartment 68 of the bracket 50. The extending end of shaft 77 carries a gear 80 which drives the gear 59. The opening 81 in the wall of the compartment 68 through which the shaft 79 extends is of sufficient size to permit the insertion of gear 80 therethrough.

15 It will be apparent, therefore, that by the removal of bolts 70, which extend through the wall 79 of the transmission housing 71, the driving unit 25 can be removed with all the parts thereof intact. The removal of 20 bolts 52 will permit the detaching of the wringer 51 from the bracket 50, the pin 66 being adapted to slide out of the slot 65 in the coupling 62.

25 In order to prevent lubricant from passing from the gear housing 58 into the wringer 51, and also in order to prevent water from passing from the wringer 51 into the gear housing 58, a plate 83 is interposed between the wringer 51 and the gear housing 58. An 30 opening 84 is formed within the plate 83, adjacent the pin 66 of the extending wringer roll shaft. The opening 84 is of sufficient diameter to permit the withdrawal of the pin 66 therethrough. A baffle 85 is carried 35 by the driving roll shaft and adjacent the opening 84 which prevents water from splashing through said opening.

40 The driving unit 24 for the washing apparatus 22 includes a gear housing similar to the gear housing 71 of the wringer unit 25. The construction and arrangement of the side frames 26 is such that it is necessary only to insert a spacing member or adapter 45 86 between the wall 79 of the housing 71 and the frame 26, in order to mount same upon the frame 26. The spacing element 86 is provided with a flange 87 adapted to receive bolts 87^a by which said spacing element 86 is secured to the frame 26. The housing 71 50 is secured to the spacing element 86 by bolts which are secured to said spacer 86 and the wall 79. The mechanism within the housing 71 of unit 24 is substantially the same as that within the housing 71 of unit 25, except 55 that in the unit 24 a shaft 88 is substituted for shaft 77 of unit 25. Shaft 88 is somewhat longer than the shaft 77 due to the fact that said shaft must extend through the spacer 86. The end of shaft 88 carries 60 a gear 89 which drives the segment 40 of the washing apparatus 22. It will be noted that the opening 90 within the side frame 26 is large enough to receive the gear 89, whereby the gear may be withdrawn or inserted 65 therethrough.

The tub 35 is removable from the supporting frame without disturbing the sector 40 as is clearly shown and described in the previously mentioned copending application.

70 Since the housings 71 are the same for both the washing machine driving unit and the wringer driving unit, and by the provision of the spacer 86, the cost of manufacture of the laundry machine has been minimized.

75 The electrical circuit for the driving unit 25 includes wires (not shown) which are disposed within the hollow bracket 50 and connected with terminals 95 and 96 of a terminal block 97. The bracket 50 is bulged outwardly to form a conduit 98. The lower end 80 of the conduit 98 terminates above the terminal block 97 and the upper end merges into an opening 99 adjacent the opening 81 but separated therefrom by a wall 100. Opening 99 registers with an opening 101 85 in the wall 79 of gear housing 71 and forms a conduit leading to the interior of the motor frame 73. In this manner a conduit is formed from the terminal block 97 to the interior of the motor frame 73 which is 90 isolated from that portion of the gear housing 71 containing the gearing, and from housing 58 and compartment 68. The wires 103 and 104 for the wringer driving unit 25 extend through this conduit, and are connected to the terminals 95 and 96, and with the motor in a suitable manner. The wires are isolated so that water and oil is kept out of contact with the wires.

95 Wires 105 and 106 for the motor of unit 24 100 extend through the opening 90 in the frame 26 and thence through opening 101 in gear housing 71 to the interior of the motor. When it is desirable to remove the units 24 or 25, the wires to the motor can be disconnected at a terminal block (not shown) and at terminal block 97, respectively.

105 It will be noted that the driving mechanisms for the wringer and the washing machine tub are similar in the following particulars. Each of these driving mechanisms include a vertically extending frame which supports the power driving unit on one side thereof and the work machine on the other side thereof. The work machine, when attached to the frame, cooperates with the frame to provide a housing for a gear or other motion transmitting member connecting the driving unit with the work machine. The work machine is removable from the frame and disconnectible from the gear 110 associated with the frame while the gear, frame and driving unit remain assembled. Likewise the driving unit is removable from the frame and disconnectible from the gear 115 supported by the frame while the gear, frame and work machine remain assembled. It will be also noted that the screws or other devices used to attach the power driving unit 120 to the frame are accessible adjacent the side 125 130

of the frame upon which the driving unit is mounted in order that the driving unit may be removed from the frame without requiring the work machine to be disassembled 5 from the frame.

While the form of embodiment of the invention as herein disclosed, constitutes a preferred form, it is to be understood that other forms might be adopted, all coming 10 within the scope of the claims which follow.

What is claimed is as follows:

1. A driving mechanism comprising, in combination, a frame having an aperture through a side wall thereof, a power driving unit attached to said side wall and covering said aperture and having a shaft extending through said aperture, a work machine supported by said frame and cooperating therewith to provide a gear housing, a gear with- 20 in said housing and supported by the frame, and a gear on said shaft meshing with said first gear, the power unit and the work machine each being separately and independently removable from the frame, leaving 25 the second gear assembled with the frame.

2. A driving mechanism comprising, in combination, a frame having an aperture through a wall thereof, a power driving unit attached to one side of said wall and covering said aperture, a work machine supported on the opposite side of said wall, gearing connecting said unit and machine including a gear supported by the frame and a transmission member extending through the aperture, said power unit and work machine each being separately and independently removable from the frame, leaving the gear assembled with the frame.

3. A driving mechanism comprising, in combination, a frame having an aperture through a wall thereof, a power driving unit attached to one side of said wall and covering said aperture and having a shaft extending through said aperture, a work machine supported by the frame, a gear supported by the frame, and a gear on the shaft meshing with said first gear, the power unit and the work machine each being separately and independently removable from the frame, leaving the second gear assembled 50 with the frame.

4. A driving mechanism comprising, in combination, a frame having an aperture through a wall thereof, a power driving unit attached to one side of said wall and covering said aperture, and having a shaft extending through said aperture, a work machine supported by the frame, a gear supported by the frame, a rotatable member of

the work machine connected with the gear 60 and disconnectible therefrom by the removal of the work machine from the frame, and a gear on the shaft meshing with said first gear, the power unit and the work machine each being separately and independently 65 removable from the frame, leaving the second gear assembled with the frame.

5. A driving mechanism comprising, in combination, a work machine, a frame supporting the work machine, the latter co-operating with the former to provide a gear housing, a gear supported by the frame and located within the gear housing, a rotatable member of the work machine connected with the gear and disconnectible therefrom by the removal of the work machine from the frame; and a power driving unit comprising a motor, a gear reduction gearing connecting the gear with the motor shaft, and a housing for the reduction gearing, said 80 housing being detachably connected with frame and the gear of the unit meshing with the first gear when the unit is assembled with the frame.

6. A driving mechanism comprising, in combination, a work machine, a frame supporting the work machine, the latter co-operating with the former to provide a gear housing, a gear supported by the frame and located within the gear housing, a rotatable member of the work machine connected with the gear and disconnectible therefrom by the removal of the work machine from the frame; and a power driving unit comprising a housing, a driving shaft within 90 said housing, a second gear carried by the shaft and adapted to be connected with said first gear, said housing being detachably connected with the frame, and the second gear meshing with the first gear when the unit is assembled with the frame.

7. A driving mechanism, comprising in combination, a frame providing a gear housing, a motion transmission member movably carried by said frame within said housing, 105 a work machine removably attached to said frame and having a transmission member connected with said first member and disconnectible therefrom by the removal of said machine, and a power driving unit supported 110 by the frame and connected with said first member, the unit being removable from the frame while said member, frame and machine remain assembled.

In testimony whereof I hereto affixed my 115 signature.

RALPH L. LEE.
